UNITED STATES PATENT OFFICE.

CHARLES E. EVELETH, OF SCHENECTADY, NEW YORK, ASSIGNOR TO GENERAL ELECTRIC COMPANY, A CORPORATION OF NEW YORK.

ELECTRIC SWITCH.

No. 844,787.

Specification of Letters Patent.

Patented Feb. 19, 1907.

Application filed June 23, 1903. Serial No. 162,773.

To all whom it may concern:

Be it known that I, CHARLES E. EVELETH, a citizen of the United States, residing at Schenectady, in the county of Schenectady, State of New York, have invented certain new and useful Improvements in Electric Switches, of which the following is a specification.

This invention relates to switches for controlling electric circuits; and its object is to improve the operation of the switch and prevent the deterioration of the secondary or auxiliary contacts at which the arcing takes place.

In switches for handling heavy currents it is customary to provide, in addition to the main switch-blade and clip, a pair of secondary contacts, one of which is composed of material having a high melting-point, such as carbon, said contacts being arranged to close in advance of the main blade and to open after it has left its clip, so that any arcing which occurs may be confined to the secondary contacts. Unless the secondary contacts are in good contact when the main blade leaves the clip there may be a slight burning of the clip. Moreover, the repeated arcing has a tendency to roughen the surface of the metal secondary contact.

The object of my invention is to produce a good contact between the secondary contacts when the blade leaves the clip and also to provide one of the secondary contacts with an abradant, so that when they rub together in opening or closing the switch the metal contact will be smoothed and polished and kept in good condition.

In the accompanying drawings, Figure 1 is a side elevation of a switch embodying my improvements, the switch being closed. Fig. 2 is a similar view, showing the switch in arcing position; and Fig. 3 is an end view of the switch in the position shown in Fig. 2.

The main blade 1 is pivoted to the hinge-clip at 2 and closes in the clip 3. Secured to the main blade is a metal holder 4, in which is held a secondary contact 5, composed of some refractory conductor, such as carbon.

A resilient arm 6 is attached to one side of the clip 3, and supported on the arm is the other secondary contact 7, preferably a block of copper. The co-operating faces of the two secondary contacts are curved, and their arrangement is such that at the instant the

main blade leaves the clip the contact area and pressure between the blocks is at a maximum, they being pressed firmly together by the spring-arm 6, as indicated in dotted lines in Fig. 1. This causes the circuit through the secondary contacts to be of comparatively low resistance and saves the clip from being burned. When the switch has been opened far enough to separate the secondary contacts, the arcing occurs at points removed from the effective contact-surface, taking place at the angle 8 of the block 5 and the tip 9 of the block 7. The actual contact-surfaces are thus preserved from roughening, and the carbon block is therefore worn away but slowly; but the contact-surfaces are liable to become smoked, and in order to polish them I prefer to use in connection with the carbon block an abradant, preferably incorporated in the carbon. A mixture of carbon and carborundum or carbon and emery is efficient, and when a block of such a mixture is dragged over the copper or other metal contact 7 it cleans, smooths, and polishes it, and thus keeps it in condition to make good electrical contact with the block 5.

The carbon or other block 5 is preferably soldered into the holder 4, so as to make a good electrical connection therewith. In addition to the soldering a pin or rivet 10 may be used to fasten the block and the holder together, so that when the switch opens an excessive overload, heating the carbon so hot that the solder melts, the pin will hold the block in place until the solder can harden. The holder is secured to the switch-blade by means of a flange 11, in which is a hole through which passes the screw-threaded stud 12, by which the removable handle 13 is attached to the piece 14 on the end of the blade.

In accordance with the patent statutes I have described the principle of my invention, together with the apparatus which I now consider to represent the best embodiment thereof; but I desire to have it understood that the apparatus shown is only illustrative and that the invention can be carried out by other means, being applicable to switches, cut-outs, circuit-breakers, and all apparatus for opening and closing an electric circuit.

What I claim as new, and desire to secure by Letters Patent of the United States, is—

1. A switch-contact consisting of a homo-

geneous mixture of a refractory conductor and an abradant.

2. A switch-contact consisting of a homogeneous mixture of carbon and carborundum.

5 3. The combination with a switch, of secondary contacts, one of which consists of a homogeneous mixture of carbon and an abradant.

4. In a switch, the combination with the main blade and its removable handle, of a secondary contact secured to said blade by said handle.

5. In a switch, the combination with the main blade, of a handle having a screw-threaded stud, and a holder for a secondary contact provided with a flange having a hole through which said stud passes. 15

In witness whereof I have hereunto set my hand this 22d day of June, 1903.

CHARLES E. EVELETH.
